UNITED STATES PATENT OFFICE.

WILLIAM J. STEWART, OF MINNEAPOLIS, MINNESOTA.

KNIFE-GUARD.

SPECIFICATION forming part of Letters Patent No. 655,280, dated August 7, 1900.

Application filed February 17, 1899. Serial No. 705,764. (No model.)

To all whom it may concern:

Be it known that I, WILLIAM J. STEWART, a citizen of the United States, residing at Minneapolis, in the county of Hennepin and State 5 of Minnesota, have invented certain new and useful Improvements in Knife-Guards for Jointers; and I do hereby declare the following to be a full, clear, and exact description of the invention, such as will enable others 10 skilled in the art to which it appertains to make and use the same.

My present invention has for its object to provide an improved knife-guard for jointers and similar machines; and to this end it consists 15 of the novel devices and combinations of devices hereinafter described, and defined in the claim.

The invention is illustrated in the accompanying drawings, wherein like characters indicate 20 like parts throughout the several views.

Figure 1 is a plan view of a jointer with my improved knife-guard applied in working position thereto. Fig. 2 is a side elevation of the jointer and knife-guard shown in Fig. 1. Fig. 3 is a plan showing in detail the knife-guard removed from working position, and Fig. 4 is a longitudinal vertical section taken 25 on the line $x^4 x^4$ of Fig. 3.

Of the parts of the jointer, 1 indicates the 30 standard or base; 2, the face or bed plate; 3, the adjustable work-guide or straight-edge bracket, and 4 the tool-shaft, suitably mounted in the ordinary manner and provided with the ordinary cutter 5 and a pulley 6, by means 35 of which it is driven.

The knife-guard comprises a spring-arm a , which is secured at one end, as shown at a' , to the bed-plate 2 and is provided at its free end with a plate-like knife-guard a^2 , which 40 under the action of the spring-arm a is normally held immediately over the cutters 5. At its forward edge the guard-plate a^2 is beveled or provided with a cam-surface, as shown at a^3 , and, as shown, it is provided at its under 45 surface with a transversely-extended concave or channel a^4 , which gives clearance for the cutters or knives.

A piece of work z is indicated by dotted

lines in Fig. 1. When such a piece of work is placed against the guide 3 and forced over 50 the knives or cutters 5, it will before reaching the knives engage the beveled or cam surface a^3 of the guard-plate a^2 and cam the same outward out of the way, as shown by dotted lines in Fig. 1. When the piece of 55 work z has been forced past the knives or if by accident or otherwise the piece of work is raised or thrown upward before the work thereon has been completed, the guard-plate a^2 will be instantaneously thrown over the 60 knives by its spring-arm a .

The device above described is very simple, is of but very small cost, and I have found the same in practice to be very efficient for the purpose had in view. The cam-actuated 65 guard-plate above described need not be very large, but only large enough to cover the cutters or knives when in its normal position.

The dangers encountered in the use of machines of the character above described without a guard for the knives or cutters are a matter of common knowledge, and the importance of a simple and efficient guard or safety device which will not interfere with the work, but will prevent the fingers from 70 being brought into contact with the knives, 75 will be readily appreciated.

What I claim, and desire to secure by Letters Patent of the United States, is as follows:

The combination with a jointer or similar 80 machine, of a knife-guard comprising the arm a of spring material, secured at one end to the bed or face plate of the machine, and provided at its free end with the rigidly-secured guard head or plate a^2 , normally overlying the cutters and, movable flatwise over the face of the bed-plate, being supported thereby, and having the inclined or cam surface a^3 , said parts operating substantially as and for the 85 purposes set forth.

In testimony whereof I affix my signature in presence of two witnesses.

WILLIAM J. STEWART
